Primary Examiner — Amanda Christensen(74) *Attorney, Agent, or Firm* — The H.T. Than Law Group(57) **CLAIM**

The ornamental design for a charger for shaver as shown and described.

DESCRIPTION

FIG. 1 is a top perspective view of a charger for shaver according to the present invention;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the charger for shaver that form no part of the claimed design.

1 Claim, 5 Drawing Sheets(56)
